CLAIM

The ornamental design for a visual water shower dispenser, as shown and described.

DESCRIPTION

FIG. 1 is a perspective view of a visual water shower dispenser, showing my new design, which allows the viewing of water therein being dispensed

FIG. 2 is a frontal plan view thereof.

FIG. 3 is a right side elevational view thereof.

FIG. 4 is a rear elevational view thereof.

FIG. 5 is a left side elevational view thereof

FIG. 6 is a top plan view thereof; and,

FIG. 7 is a bottom plan view thereof.

Broken line illustrations of balls floating within visual water shower dispenser in the drawings, are not part of the design sought to be patented.
